PREPAYMENT MECHANISM

George Edward Weston, Enfield, England, assignor to Sangamo Electric Company, Springfield, Ill.

Application February 12, 1938, Serial No. 190,180
In Great Britain February 16, 1937

7 Claims. (Cl. 194—1)

The present invention relates to prepayment mechanisms which, while particularly applicable to the controlling of electric supply meters, are also capable of application in a much wider sphere as will readily be appreciated.

The principal object of the invention is to relieve the user of the necessity of effecting some or all of the operations incidental to the insertion of a coin; which operations consist, for instance, in gauging the coin, setting gear mechanism in accordance with the value of the coins, operating the gear mechanism in accordance therewith, operating a device to effect the supply of the commodity (for instance in the case of an electric supply meter, closing the switch), rejecting faulty coins, collecting the coin after gauging has been completed, and testing coins for various properties.

Another object of the invention is to prevent any access to any part of the mechanism through the coin insertion or like aperture during the whole of the period of time when the various operations incidental to the insertion of such coin are being effected.

Another object of the invention is to provide an improved arrangement for receiving the inserted coin whereby provision may be made for the insertion of extra thick coins such as the new British threepenny piece, while at the same time avoiding the possibility of jamming of the apparatus by the simultaneous insertion of two thinner coins.

A further object of the invention is to provide an improved coin testing mechanism for checking both the diameter and the thickness of the inserted coin.

Another object of the invention is to provide an improved switch setting and tripping mechanism by which the frictional load imposed upon the meter mechanism controlling such switch is reduced or avoided.

Yet a further object of the invention in the case of its application to electricity meters, is to provide a warning for the user that his credit is approaching exhaustion while another object is to improve the means for handling unsuitable coins.

According to one feature the invention as applied to a multi-coin prepayment meter for electricity or gas, consists of the employment of an auxiliary source of power such as supply of electricity or a stressed spring for effecting certain or all of those operations which are normally performed by the user.

According to a supplementary feature of the

invention in particular connection with devices operable by any one of a number of differently valued coins, the operator effects an initial step such as inserting the coin and releasing or otherwise permitting the movement of a device whereby the coin advances to a position which it could only reach by such movement or gauging of the coin and thereby closing one of a number of different electrical circuits according to the diameter of the inserted coin, a circuit closure following upon such initial step resulting in the remaining operations being brought about automatically.

According to yet another feature of the invention the whole of the operations are effected independently of the user once the coin slot has been opened, the coin inserted and the coin slot reclosed.

According to yet a further feature of the invention a coin receiving chamber or cage is provided which is movable to receive an inserted coin and also to prevent the insertion of coins of more than a total predetermined thickness.

According to a further feature of the invention the auxiliary driving power source is put into operation by the insertion of a coin and continues to operate the meter mechanism through a complete cycle of operations irrespective of whether the inserted coin is satisfactory or not, but only effects a registration of the value of such coin if it passes all of the tests applied to it.

According to a further feature of the invention as applied to prepayment meters for electricity a device is provided by which an intermittent interruption of the supply is effected immediately prior to the point of cutting-off of the supply by the meter mechanism due to exhaustion of the user's credit therein.

In order that the above and further objects and features of the invention may be more readily understood a constructional embodiment will now be described with reference to the accompanying drawings, wherein:

Fig. 1 is a front elevation of a prepayment mechanism according to the present invention in association with an electric watt-hour meter mechanism;

Fig. 2 is a plan view of the mechanism shown in Fig. 1;

Fig. 3 is a sectional elevational view drawn to an enlarged scale and taken along the line III—III of Fig. 2;

Fig. 3A is a detail view showing a portion of the arm 118 and the cam 119 in elevation;

Fig. 3B is a top plan view of the slide plate

142a, showing its relation to the pin 142b, just prior to engagement therewith;

Fig. 4 is a sectional elevational view also drawn to an enlarged scale and taken along the line IV—IV of Fig. 2;

Figs. 5 and 6 are fragmentary plan views showing the construction and manner of operation of the coin receiving mechanism;

Fig. 7 is a fragmentary plan view showing the caliper and thickness testing mechanism;

Fig. 8 is a circuit diagram of the driving motor and its controlling switch contacts;

Figs. 9 and 10 are detail views taken at right angles to one another of the switch closing and latching mechanism and part of the automatic warning device;

Figs. 11 and 12 are detail views of the device for giving warning to the user of impending exhaustion of credit;

Fig. 13 is a schematic view showing the arrangements of the various gear trains of the meter mechanisms;

Fig. 14 is a diagrammatic view in perspective of a modification;

Fig. 15 is a plan view of certain details of construction shown in elevation in Figs. 3 and 4;

Fig. 16 is vertical sectional view of certain details of the warning mechanism; and

Figures 17 and 18 are different views of a gear shifting lever.

Figures 1 and 2 show the prepayment mechanism indicated generally by the reference numeral 10 located within a casing A and provided with a device 11 for collecting a fixed charge and attached to a watt-hour meter or integrating mechanism 12. The latter may be of any desired and known construction giving a rotary movement proportional to the consumption being measured and in the example shown comprises the usual disc-motor element 13 carried upon a motor shaft 14 and moving between pole tips 15. The motor shaft 14 drives the gear wheel 16 through a suitable reduction gear train and also operates an integrating gear train actuating a plurality of recording dials 17.

The prepayment mechanism 10 (see more particularly Figures 1 to 4) comprises generally a coin receiving mechanism 18 for dealing with the coins fed to the mechanism by the user, coin testing mechanism 19 to which coins are fed by the coin receiving mechanism and by which the inserted coins are tested with regard to certain properties such as diameter, thickness and electrical conductivity so that the subsequent operation of the meter can be controlled in accordance with the results of such tests, switch closing mechanism 20, registering or credit mechanism 21 influenced in one (i. e. crediting) direction by operation of the coin testing mechanism 19 upon an acceptable coin and in an opposite (i. e. debit or arrears) direction by movement of the watt-hour meter mechanism 12 and the fixed charge collector 11, switch controlling mechanism 22, Figure 9, influenced by the setting of the registering mechanism 21, automatic credit exhaustion warning device 23, Figure 9, and an auxiliary driving power source in the form of a driving motor 24 for effecting the whole of the operation of the mechanism at each coin insertion without any manual effort over and above that of inserting a coin into the mechanism.

The coin receiving mechanism illustrated more particularly in Figures 1, 2, 3, 5, and 6 comprises a coin cage 25 formed of insulating material such as a moulded plastic material, secured

to the upper end of a lever 26 pivoted at its lower end at 41 to one of the frame-plates 27 of the mechanism. A masking plate 28 provided with a restricted coin slot 29 is secured to the front of the cage 25 and slides upon the rear surface of a stationary block 30 secured to the front frame-plate 27. The block 30 is provided with a coin insertion aperture 31 therein at a position normally out of register with the slot 29 and also has a manually operable flap 33 secured to a spindle 32 pivotally mounted therein. The spindle 32 has a forked lever 34 secured thereto at its upper end. The fork of this lever receives one end of a spring 35 secured at its other end to the top of the cage 25. This cage is normally urged to occupy the position shown in Figures 2, 3, and 5 by a helical spring 36 anchored at one end to the cage and at its other end to the block 30; this spring, acting through the spring 35 which is much stronger than the spring 36, also serves normally to maintain the flap 33 closed upon the insertion aperture 31.

The interior of the cage 25 is of considerably greater width than that of any coin or plurality of coins that it is possible to insert through the coin slot 29 and the insertion aperture 31 and is provided in one side wall thereof with an transverse slot 37 which permits the passage into the interior of the cage of one edge 38 of an abutment plate 39 fixed to one of the frame plates 27. The edge 38 is stepped by means of an inclined surface 40 to provide a proud portion 45 which causes the effective width of the coin cage 25, when its slot 29 is in register with the aperture 31, to be less towards the back than at the front. The cage 25 moves about the pivot 41 with its open bottom aperture 42 located immediately above the upper surface of a platform 43 formed upon a second or coin testing chamber 44 in all of its positions except its extreme left-hand or normal position (Figures 2, 3, and 5) where the bottom aperture 42 is in register with the lower chamber.

The coin testing chamber 44 is formed with two spaced-apart side walls 46, 47, and a rear end wall 48. The chamber is formed of insulating material, such as a mouldable plastic material, and is provided with a metal insert or plate 49 on the inner surface of the side wall 46 and with a hinged light metal flap 50 secured to the inside of the opposite side wall 47. These metal members are located adjacent the rear wall 48 and form one electrical contact for engaging an inserted coin. The bottom of the coin testing chamber 44 is normally closed by a member 51 of sector-shaped cross-section also formed of insulating material and provided with a metal top plate 52 constituting a second electrical contact for engaging the inserted coin.

The member 51 is secured near its lower edge upon a spindle 53 pivotally mounted in the frame plates 27. This spindle is provided near its rear end with a two-armed catch lever 54 (Figure 4) which serves to control the movement of the member 51 in a manner hereinafter described.

The operation of this portion of the device which requires a manual movement to effect each coin insertion is as follows. The flap 33 is opened manually, thereby rocking the forked lever 34 to the right (Figure 6). This operation moves the cage 25 bodily through the stiff spring 35, and stresses the helical spring 36 until the slot 29 in the masking plate 28 comes into register with the coin insertion aperture 41 in the block 30. A coin or like article can now be inserted and if it

is not more than a certain predetermined thickness it will pass into the cage 25 between the left-hand wall thereof (Figure 6) and the proud portion 45 of the abutment plate 39. Release of the flap 33 will then allow the spring 36 to cause this to close and the cage to move to the left (Figure 5) with the coin therein resting upon the platform 43 until the bottom aperture 42 of the cage registers with the coin testing chamber 44, whereupon the coin or like article will drop into the latter for further handling.

In the event of excessive thickness of the coin, or in the event of the insertion of a plurality of thin coins at one time through the aperture 31 and the slot 29 such coin or coins will come into engagement with the inclined surface 40 of the fixed abutment plate 39 and upon further forcing pressure being applied will be forced between the proud edge portion 45 and the opposing wall of the cage. Such action will result in bodily movement of the cage to the left, such movement being permitted without closure of the flap 33 by the flexing of the stiff spring 35. This movement of the cage will result in equivalent movement of the masking plate 28 with the result that the coin slot 29 will no longer be in exact register with the aperture 31 and the effective passageway is decreased in width to prevent the insertion of further coins. A similar action takes place if attempt is made to insert a second thin coin after a first coin and while it may be possible to force a coin or coins into the cage, such action automatically causes a restriction in size of the insertion aperture available thereafter. When, as in the case of the new British threepenny piece, a coin of excessive thickness but small diameter is to be dealt with, in addition to the usual range of coins, the inclined surface 40 is arranged in such a position that the said thick coin can be accommodated wholly within the cage without having to ride up the said inclined face. After insertion of the coin (or coins if one or more further coins have been forcibly inserted in the manner described above) the release of the flap 33 causes the movement of the cage away from the abutment plate 39 with the result that the coin (or coins) are loosened within the cage and are perfectly free to drop into the coin testing chamber 44 when the cage bottom aperture 42 registers therewith. It will also be appreciated that the masking of the coin passageway by the flap 33 and the masking plate 28 prevents any possibility of access to the interior of the mechanism through such slot.

The coins or other article thus delivered to the chamber 44 drop between the metal plate 49 and the flap 50 and rest upon the contact plate 52 of the sector shaped coin chamber closing member 51 that is mounted on a shaft 53. If, as is the case with a coin, the inserted article is conductive the electromagnetic auxiliary driving power source or motor 24 is immediately actuated.

The circuit diagram of Figure 8 shows how a conductive coin *x* bridges the contacts 49, 50, and 52 to complete a circuit from mains lead 56 through an electromagnetic driving motor coil 57 of the motor 24 to the other mains lead 58. Immediately the motor 24 commences to operate, it completes at contacts 59 a further circuit shunting the coin contacts 49, 50, and 52. These shunting contacts 59 are, as illustrated in Figure 4, controlled by a cam 60 secured to a shaft 61 which is in driving connection with the motor 24 and makes one revolution for every operative

cycle of the mechanism. It will be seen that the relieved portion of the cam 60 (Figure 4) is normally opposite a projecting cam follower 60a on the switch contacts 59 and these are thus open.

- 5 Upon initial energization of the motor 24 through the coin bridged contacts the cam 60 is moved sufficiently to cause closure of contacts 59 which are then maintained closed, irrespective of the removal of the coin from the chamber 44, until the cam has completed one revolution back to its initial position where, the coin having meanwhile been removed from the chamber 44, the motor circuit is broken. The contact pressure between the hinged flap 50 and the opposing metal insert 47 is regulated to be as light as possible in order to avoid holding of the coins out of contact with the contact plate 52. This regulation is effected by means of a bell crank lever 62 (Figure 3) pivoted at 63 to one of the frame plates 27 and provided at its upper end with a nose piece 64 of insulating material projecting through an aperture in the side wall 47 of the chamber 44 to engage the flap 50. The pressure of the nose 64 upon the flap is regulable by a counterweight 65 secured to the other arm of the lever 62 while a lug 66 is also provided on the said lever in the path of the sector-shaped member 51 for a purpose herein-after described.

The auxiliary driving power source is in the form of an alternating current motor 24. This motor comprises a laminated field structure 67 provided with the coil 57 and an armature tunnel 68 containing a polarised armature 69 loosely mounted on a rotatable shaft 70 carried in bearing plates 71 secured to the field structure 67. The armature 69 is anchored at one end to each side of the armature tunnel by opposed springs 72 which allow the armature to vibrate when alternating current is fed to the winding 57. 20 This vibratory motion of the armature is translated into uni-directional rotary motion of the shaft 70 by means of a pair of pawls 73 carried by the armature engaging a ratchet wheel 74 secured to the shaft, any backward movement of the shaft being prevented by further pawls 75 secured to the bearing plates 71 and also engaging the said ratchet wheel. It will be understood that any other suitable form of driving motor may be employed depending upon the current supply available.

The coin testing mechanism 19 will now be described. The motor shaft 70 carries at one end a pinion 76 (Figure 4) driving through idler gears 77, a spur wheel 78 rigidly secured to the shaft 61. The spur wheel 78 meshes with an identical spur wheel 79 carried by but not positively fixed to a spindle 80 also rotatably mounted in the frame plates 27.

The thickness testing section of the coin testing mechanism comprises a cam 120 rigidly secured to the shaft 61 and having a notch 121 in its periphery which latter is engaged by the nose 122 of a lever 123 pivoted at its upper end 124 to one of the frame plates 27. This lever carries a plunger rod 125 arranged to pass under the action of a spring 127, through a hole 126 (Figure 7) in the side 47 of the chamber 44 so as to engage the thickness dimension of any coin therein. The lever 123 extends downwardly and is provided with a tail 128 which can, under some circumstances, engage a part 134 of a detent device 129 carried by a shaft 130 which is provided at its rear end (Figure 4) with an arm 131 acting upon a pin 132 secured in a pivoted bar 119. The detent device 129, shown in detail

in Figure 15, comprises an arm 250 rigidly secured to the shaft 130 and provided with a projecting lug 251. The part 134 is loosely mounted on the shaft 130 and rests upon a set screw 133 which projects through the lug 251, Figure 3. The position of the part 134 is adjustable with respect to the shaft 130 by adjustment of the set screw 133. The bar 110 is pivoted at one end to the frame and is spring urged upwardly against a stop pin 252 by a spring 253 and at its other end has a projecting lug 111 normally engaging the catch lever 54 secured to the spindle 53 and controlling the member 51 closing the chamber 44.

In the operation of this part of the coin testing mechanism, upon rotation of the shaft 61 by the power source 24 in the direction indicated by the arrow 61a, Figure 3, the nose 122 drops into the notch 121 and allows the plunger rod 125 to project into the chamber 44. Such movement causes the tail 128 of the lever 123 to move towards the detent device 129. This device 129 is so adjusted as to its position that the tail 128 of the lever 123 does not engage therewith when the plunger rod 125 contacts with a coin of at least a certain predetermined thickness within the chamber 44. If, however, the coin is of less than such predetermined thickness or is absent or pierceable the tail 128 moves far enough to engage the part 134 and so to rock the device 129, the shaft 130 and the arm 131 which in turn depresses the bar 110 against the action of spring 253 to remove lug 111 from engagement with catch lever 54. Such release of catch lever 54 permits the spring 112 to move the coin chamber closing member 51 to the left (Figure 3) in a direction to pass the coin down the right-hand side of the member 51 to the returned-coins chute or the like. The member 51 is rocked in the opposite direction (to the right Figure 3) if the coin has proper dimensions in a manner hereinafter described.

The plunger rod 125 is almost immediately retracted by the cam 120 and the coin if of wrong thickness or pierceable is thus removed from the chamber 44 before the caliper movement which follows immediately takes place.

In order to avoid any possibility of light cardboard discs or light metal slugs being retained between the flap 59 and the plate 49 the member 51 is arranged to engage the lug 66 on the bell crank 62 during its rocking movement to discharge a coin and thus to remove any pressure of the nose piece 64 upon the flap 59.

The diameter caliper section of the coin testing mechanism comprises a snail cam 81, Figures 3 and 7, rigidly secured to the shaft 61 and having a contoured surface engaged by a cam follower 82 integral with a sleeve 83 which is freely rotatable about a vertical spindle 84 rotatably mounted in bearing brackets 85 secured to the front plate 27 of the mechanism. The spindle 84 has a lever having two arms 86, 87 (Figures 3 and 7) rigidly secured thereto, one arm 86 being linked to a caliper slide 88 mounted for transverse movement across the coin testing chamber 44 and acting to caliper the diameter of a coin located within the testing chamber. The other arm 87 is provided at its end with a roller 87a retained within a groove formed in a multiple section gear unit 89 and operates to slide the latter along the squared portion of the spindle 80. The ratio of lengths of the arms 86, 87 is made such that the move-

ment of the gear unit 89 is an amplified version of the movement imparted to the slide 88.

The spindle 84 and the lever 86, 87 are connected to one end of a helical spring 104, Figure 3, anchored at its other end to the fixed frame of the mechanism. This spring 104 acts to urge the lever 86, 87 in a direction to move the caliper slide 88 against a coin in the chamber 44 but is prevented from such action when the follower 82 is resting against the proud part of the cam 81 by the opposition of the stronger helical spring 105 connected between the cam follower 82 and the spindle 84.

When the cam follower 82 rests against the cam 81, as shown in Figures 3 and 7, it acts through the relatively strong spring 105 to hold the spindle 84 and therewith the lever 86, 87 against the biasing force of the relatively weak spring 104 with the caliper slide 88 in the inoperative position, Figure 7. The spring 105 permits continued movement of the cam follower after the caliper slide 88 has been fully withdrawn from the coin chamber 44, thus ensuring that it is completely withdrawn. It will thus be apparent that the cam 81 and its follower 82 serve to move the caliper slide 88 into and out of operative position in the coin chamber 44, the final caliper movement being under the control of the relatively weak spring 104. Also, the multiple unit gear 89 is moved together with the lever 86, 87 back to their initial positions by the cam 81 following completion of the coin caliper cycle. Since the movement of the lever 86, 87 depends upon the size of the coin being caliper and is, of course, variable some such connecting mechanism such as that described employing the springs 104 and 105 and associated parts must be used to perform all of the required operating functions.

In the operation of this section of the coin testing mechanism, the rotation of the shaft 61 and cam 81 releases the cam follower 82 which can then move towards the shaft and relieve the tension on spring 105. The spring 104 now becomes effective to urge the slide 88 against any coin located within the chamber 44 and the final position in which such slide abuts the coin determines the axial position of the gear unit 89 upon the shaft 80.

The multi-section gear unit 89 is provided with a notched disc 106 which is adapted when the spindle 80 is rotated (through gears 78, 79) by the operating motor 24 to co-operate with a gauge plate 107 rigidly secured to a rock bar 108 carried in the frame plates 27. The gauge plate 107 is provided with a plurality of spaced slots located in positions which register with the disc 106 when the gear unit 89 is in any one of its positions corresponding to the caliper of a coin of acceptable diameter within the chamber 44. The alignment of the notched disc 106 with any one of these slots permits continued rotation of the gear unit 89 by the motor 24 through gears 78, 79 and shaft 80 and thus effects an appropriate amount of rotation of a gear wheel 90 in accordance with the value of the coin located within the chamber 44. For such purpose the multi-section gear unit 89 is provided with a plurality of axially spaced sets of teeth adapted in the manner above described to be brought into alignment with the gear wheel 90 secured to a shaft 91 also rotatably mounted in the frame plate 27 and in geared relation to

the credit registering mechanism 21 in a manner hereinafter more fully described.

In the event of caliperizing of a coin of incorrect unacceptable diameter within the chamber 44 the notched disc 106 will not align with any slot of the gauge plate 107 and in consequence, during rotation of the spindle 80 by the driving motor, the said disc will engage the gauge plate and cause a rotary movement of the rock bar 108 against the action of a spring 55 (Figure 4). This rock bar is secured at its rear end to a trip lever 109 (Figure 4), which bears at its lower end upon an abutment 109a secured to the pivoted bar 110. Upon movement of the rock bar 108 by the disc 106 the pivoted bar 110 is depressed, the catch lever 54 released and the member 51 rocked about its pivot towards the left (Figure 3) by the spring 112 to allow the coin within the chamber 44 to fall on the righthand side thereof (Figure 3) into a returned-coins chute or container. Referring now to Figures 4 and 7 the spur wheel 79 which is freely rotatable upon the shaft 80, is provided with a pin 113 normally projecting into engagement with the laterally projecting end 114a of a lever 114 pivoted upon a plate 115 in rigid driving connection with the shaft 80. This lever 114 is provided with a pin 116 projecting through an arcuate slot in the plate 115 into a plane where, upon rotation of the wheel 79 and the plate 115 in unison therewith, it will come under the nose 117 of the trip lever 109 so that if this latter should be rocked about its axis at this same instant by engagement of the notched disc 106 with the gauge plate 107, then the pin 116 is depressed towards the center of the wheel 79 against the action of spring 114b and the lever 114 thus moved out of engagement with the pin 113. In this manner the spur gear wheel 79 is freed and permitted to continue its rotation by the completion of the operative cycle of the motor 24. The partially rotated shaft 80 is then retracted to its initial position by the pressure of a cam-faced arm 118 (Figure 3) urged by a spring 119 upon a cam 119 carried by the said shaft 80. The arm 118 and cam 119, Figure 3A, are each provided with cooperating flat surfaces 118a and 119a respectively and are so arranged that when the shaft 80 is moved to the position where it is released from connection with the gear wheel 79, the said surfaces 118a and 119a lie at an acute angle to one another. The pressure of the arm 118 thus tends to return the shaft 80 to its original position. The rock bar 108 on being relieved of the pressure of the notched disc 106 also returns to its normal position under the action of the spring 55.

The coin cage 25 is provided with a pivotally mounted gravity pawl 135 (Figures 3, 5, and 6) carrying a pin 136 on a nose 137 thereof. A two-armed lever 138 pivotally mounted on a frame plate 27 has its upper end located within the path of the pin 136 during the movement of the cage 25 to the right (Figure 3) for the purpose of inserting a fresh coin therein. This engagement between the pin 136 and the lever 138 causes the lower end of the latter to engage the member 51 and thus to rock it to the left (Figure 3) and so cause the discharge of any object within the coin chamber 44 to the returned coins chute or the like. By this means it can be ensured that articles which are non-conductive in character and hence will fail to start the operating motor, will be discharged during the next

following coin-insertion operation and will not clog the device.

A three-armed star-shaped member 139 also pivotally mounted on a frame plate 27 has one arm provided with a magnetic armature 140 arranged to be attracted by the pole tips of the field structure 67 when the motor 24 is energized. The rotation of this member 139 by such energisation causes a flap 141 of insulating material carried by another arm thereof to be brought up into a position where it obstructs the top of the chamber 44 and prevents the passage of any further coins thereto, while at the same time the remaining arm of the member 139 raises the gravity pawl 135 into a position where the pin 136 cannot engage the lever 138 to cause the release of the coin within the chamber 44. In this manner the feeding of further coins to the device while one is being dealt with or the premature release of the actual inserted coin is prevented.

For the purpose of preventing overloading of the credit-storing mechanism by the insertion of an excessive number of coins at any one time a sliding plate 142 (Figure 3) is carried by a suitable bracket extending from the frame and is provided with a lug 142a arranged to be engaged by a pin 142b carried upon a gear wheel 164 of the registering or crediting mechanism 21. This gear wheel, shown more clearly in Figure 10, is adapted to be moved along a helical path by the bodily rotation thereof along a screwed shaft 163 in one (i. e., a debit) direction by the meter and fixed charge mechanisms 12 and 11 respectively and in the opposite (i. e., credit) direction by the gear 90 in known manner. When the gear wheel 164 has been advanced as far as is allowable in the credit storage direction, the slide plate 142 is moved by engagement of its turned up end 142a, Figure 3B, with the pin 142b and through a linking spring 163 causes the rocking of a lever 194, pivoted to the frame at 195, in such a direction that its upper end 196 engages the edge of the flap 141 and moves the latter into its position obstructing the top of the chamber 44 thereby preventing the feeding of further coins into the device. It will be recalled that the flap 141 is carried by one arm of the star-shaped member 139 which is normally controlled on energization of the motor 24 by the plate 140 of magnetic material being attracted by a portion of the leakage flux of the motor. Movement of the flap 141 is also controlled by the lever 194 whose upper end 196 is arranged to engage and move the flap 141 when maximum credit has been registered so that no additional coins are permitted to fall into the coin chamber 44. Any coins still remaining in the cage 25 will thus be held until the gear wheel 164 has retracted slightly to permit removal of the flap 141.

The continued rotation of the driving motor 24 effects a complete revolution of the spur gear gear wheels 78 and 79 and at a position near the completion of one revolution thereof a pin 143 (Figure 4) on spur wheel 78 engages the end of the catch lever 54. If a satisfactory coin has been dealt with this lever is still in the position shown and in consequence the pin 143 causes its rotation in an anticlockwise direction (Figure 4) to cause rocking of the member 51 to the right (Figure 3) and so cause discharge of the proper coin within the chamber 44 to the left of the member 51 into a coin till. It will be understood that this operation is only effective

to discharge the coin into the coin till in the event of a proper coin since the member 51 will in all other circumstances have already been moved to the left (Figure 3) to discharge the coin into the return chute at some point of the operative cycle prior to the operation above described. If, on the other hand, owing to rejection of a faulty coin this lever has been tripped by lowering of the lug 111, then the pin 143 will engage within the fork 54a of the lever 54 and rotate it in an anticlockwise direction to an extent sufficient to restore its lower end behind the lug 111 ready for the next operation.

The switch closing and controlling mechanisms will next be described. The spur gear wheels 78, 79 are each provided with an axially projecting pin 144, 145 respectively and positioned so that they both rotate in unison but in opposite directions.

Referring now to Figures 9 and 10 showing the switch closing mechanism in detail, it will be seen that these pins 144, 145 during their rotation bear upon the upper surface of a plate 146 secured to the lower end of a vertical slidable rod 147 provided at its upper end with a top plate 148 and carried in a bearing bracket 149 secured to one of the frame plates 27. A helical compression spring 150 is located between the upper surface of the bearing bracket 149 and the top plate 148 and encircles the rod 147. A further helical spring 151 surrounds a switch rod 152, preferably of insulating material, and is secured at its upper end to this rod and at its lower end to the plate 146. The switch rod 152 is arranged for vertical sliding movement within the two plate members 146 and 148 and also in an extension of the bearing bracket 149. This rod carries the movable contact of a mercury switch 153 of any suitable form controlling the main current supply from the supply mains to the user's circuit. The upper end of the switch rod 152 is provided with a latching abutment 154 which co-operates with the upper end of a latching lever 155 which is pivotally mounted to a frame plate 27 and has a lower end projecting within the path of a radially extending pin 156 secured in the shaft 80.

The plate 146 when fully depressed by the pins 144 and 145 depresses the end of a catch lever 157 pivotally mounted upon a spindle 158 carried in the main frame. This lever 157 has a lower end 159 provided with a chamfered cam surface 160 and an abutment surface 160a which cooperates with a collar 161 secured to an axially movable shaft 162 which is coaxial with the screwed shaft 163 carrying the trip wheel 164 of a known form of credit registering mechanism indicated generally by the reference numeral 21. If such credit registering mechanism is registering credit the abutment surface 160a of the end 159 rests upon the collar 161 as shown in Figures 9 and 10.

The operation of the switch closing mechanism is as follows. During each cycle of operation of the motor 24 the pins 144 and 145 are rotated in unison and if the switch is open, bear upon the plate 146, depress this with the top plate 148 to compress the spring 150 and to extend the spring 151 since the switch rod 152 will be held latched at its upper end by the engagement of the lever 155 underneath the abutment 154. At the lowest point of movement of the plate 146 and providing the credit registering mechanism 21 has been placed in credit the plate 146 will be latched by the tongue 166 of the lever

157 the latter lever being held in the position shown with the abutment surface 160a of the end 159 thereof resting on the edge of the collar 161. The end 159 of the lever 157 assumes this position by reason of the chamfered end 160 acting upon the collar 161 and causing a small and temporary movement of the shaft 162 forwardly against a spring 192. Near the end of the operative cycle of the mechanism when dealing with a satisfactory coin the pin 156 on the shaft 80 will engage the lower end of the latching lever 155, rock this from beneath the abutment 154 and allow the switch to be closed rapidly by the spring 151.

If the credit-registering mechanism is not in credit but is in arrears or debit, the collar 161 will have been displaced by release of a collar 165 from the mechanism 21 and will no longer be in position to engage with the end 159 of the lever 157. This lever will therefore not be held in the position shown to retain the plate 146 and the latter will consequently rise again with the continued rotation of the pins 144, 145 and the subsequent operation of the latching lever 155 will be ineffective.

The credit registering mechanism is substantially of the kind already disclosed in British Patent No. 414,070 and its operation is briefly that the wheel 164 is moved relatively to the screwed shaft 163 in one direction by the coin mechanism and in the opposite direction by any of the various charges to be made, for example by the fixed charge collector 11 and the meter mechanism 12. At a point where the credit of the user is exhausted a pin 164a carried by this trip wheel unlatches the collar 165 secured to the shaft 162 and allows the latter to move axially by the action of the spring 192 and thus be displaced from the path of the end 159 of the lever 157. This will allow the plate 146 to move upwardly under the influence of the spring 150 to open the switch. The incorporation of the second latching means constituted by the collar 161 and lever 157 relieves the collar 165 from all strain due to switch latching and hence relieves any burden placed upon the motor driving the fixed charge drive or the meter mechanism by such switch latching mechanism.

In order that the shaft 162 may be moved axially if necessary to present it to the catch mechanism of the registering mechanism 21 during the insertion of a fresh coin the chamfered face 160 of the lever 157 is adapted to engage the collar 161 during the movement of the lever 157 by the descending plate 146 and thus to move the shaft 162 axially to the right (Figure 10). If in the meantime sufficient credit has been imparted to the registering mechanism by the insertion of the coin, then this shaft will be held in an axial position more to the right than that previously assumed thereby by the catch mechanism of the device 21 and the lever 157 will afterwards abut thereagainst with its rear face, and its upper tongue 166 in engagement with the plate 146 will retain the latter in its lowered position.

Referring now to the meter gearing arrangements shown more particularly in Figure 13, it will be seen that the spindle 91 carrying the gear 90 which is driven from the prepayment mechanism 10 has a crown wheel 92 (Figures 2, 7, and 13) and a gear wheel 93 secured thereto. The crown wheel 92 is engaged by a pinion 94 secured to a staff 95 mounted in bearings upon the front plate 27 and carrying at its other end

a further pinion 96 meshing with a crown wheel 97 fixed to the spindle of the indicator 98 (Figures 1 and 13). The remaining indicators 99 and 100 are driven from the indicator 98 by pin and sprocket wheel mechanism 161. The gear wheel 93 is in driving connection by way of gear 254 with one sun wheel 255 of a differential gear device 102 (Figures 7 and 13), the other sun wheel 256 of which is driven from the fixed charge collecting device 11 through gear train 11a (Figures 2 and 13). The planet carrier 257 of the differential gear 102 is secured to a staff 103. The movements of the two devices 10 and 11 effective upon the differential gear 102 have a resultant which is given by movement of the staff 163. This staff is connected to a change gear device 186 (Figures 2, 4, and 13) by means of which a price change compound 187 (Figures 1, 2, and 13) can be inserted in or removed from the transmission line at will. The gear change unit 186 comprises two gear wheels 258, 259 secured to a shaft 260. The gear wheels 258, 259 are in constant driving engagement with gears 261, 262 respectively both of which are carried by a gear shift lever 212, Figures 4, 17 and 18, pivoted about the axis of the shaft 260. The gears 261, 262 are adapted to engage respectively with further gear wheels 263 and 213 according to the direction in which the lever 212 is moved. The gear 263 is secured to the staff 103 so that if this gear is engaged with the gear 261 the drive from the differential 102 to the shaft 260 is direct. If on the other hand the gear 213 is engaged by the gear 262 then the drive from the differential 102 to the shaft 260 is by way of the price change compound 187 through a pinion 264 on staff 103 and then through spindle 265. The drive from the shaft 260 is then to one sun wheel 271 (Figure 13) of a further differential 188 the other sun wheel 272 of which is driven by the meter mechanism 12 through gear train 266. The planet carrier 267 of the differential 188 is connected to a shaft 268 which is in geared connection by way of a pinion 269 with a long pinion 189 meshing with the trip wheel 164 of the registering mechanism 21 and operating to screw this wheel over a helical path backwards and forwards along the screwed shaft 163. The planet wheels 267 of the last-mentioned differential 188 are also connected by way of a suitable gear train 270 to an indicator 190 (Figures 1 and 2) operating over the scale 183. The gear change device 185 is adapted to be operated during the switch opening movement by means of a lever 191 (Figures 2, 4 and 9) the downwardly extending nose 191' of which, Figure 9, is engaged by the plate 146 and moved upwardly therewith. The lever 191 also carries a pin 210 operating upon the cammed face 211 of the gear shift lever 212. The gear lever 212 is shifted in one direction by movement of the lever 191 upwards due to opening of the switch, the pin 210 carried by the lever 191 engaging the cammed face 211, and in the other direction by engagement of a pin 215 on the plate 115 with a cammed face 212' on the gear lever 212 when this is rotated at the next coin insertion operation. It will be understood that the cammed faces 211 and 212' are on extensions which may be integrally formed with the lever 212 carrying the gears of the gear change device 186 which lever can be rocked slightly so that either gear wheel 263 or 213 is engaged depending upon the direction in which the lever 212 is moved. By this means the indications given by the pointer

190 are in units unused while the mechanism is in credit and in the cash value of arrears when the mechanism is in arrears.

In order to warn the user that the supply of electricity will shortly be cut off owing to exhaustion of credit, a warning device 23 is preferably provided. This device shown more clearly in fragmentary views (Figures 9, 10, 11, and 12) comprises an operating solenoid 168 secured to 10 a part of the fixed frame and operable upon an armature 170 carried in a sleeve 171 of non-magnetic material. This sleeve is connected to an extension 169 of the main switch rod 152 by a pin and slot connection which allows the latter 15 to be operated in the normal manner previously described, by the meter mechanism without imparting movement to the armature 170.

The armature 170 is guided within pole tips 167 and 167a forming part of a magnetic circuit around the solenoid coil 168 and is normally located within the lower pole tip 167 so that when the coil 168 is intermittently energised, the said armature will be alternately raised and lowered to effect a similar movement of the switch rod 152 and thus cause flashing of any light connected to the user's circuit. The upward movement imparted to the rod 152 by the solenoid is insufficient to cause latching by the lever 155.

The intermittent energisation of the solenoid 30 168 is effected by means of the mechanism illustrated more particularly in Figures 11, 12, and 16. This device comprises a crank lever 171' which is rigidly secured to the shaft 61 and therefore makes one complete revolution during each 35 coin insertion. A lever 173 is loosely mounted on the same shaft 61 and is also slidable thereon in the direction of its length by the provision of a slot 174. A spring 175 tensioned between a pin 176 on the lever and the shaft 61 tends to move the end of the lever 173 carrying a pin 172 outwardly in a radial direction. The pin 172 projects on both sides of the lever, one side being adapted for engagement in some circumstances with the crank lever 171' and the other side being arranged to project into a radial slot 178 in a gear wheel 177 loosely mounted upon the shaft 61 and also, in some circumstances into a radial slot 179 formed in a stationary barrel 180. This barrel houses a helical spring 181 connected at one end to the barrel and at its other end to the gear wheel 177. The spring 181 normally urges the gear wheel and therewith the lever 173 in an anti-clockwise direction (Figures 11 and 12). A further lever 182 secured to a spindle 271' pivotally mounted in the fixed frame has a nose 182a which engages the pin 172 located within the slot 179 and serves, when required, to move the said pin and the lever 173 radially inwards against the action of the spring 175. The lever 182 is controlled by the trip device of the credit- 40 registering mechanism 21 through suitable linkage in such a manner that the said lever is moved to depress the pin 172 inwardly when the credit mechanism reaches a position just prior to the instant of release of the collar 161 and the consequential opening of the main switch. This movement may be effected as shown in Figure 10 by the engagement of a pin 168a carried by the trip wheel 164 with a detent 216.

The gear wheel 177 is in mesh with a smaller diameter pinion 184 which is secured to a shaft carrying a cam 184a controlling the opening and closing of switch contacts 185. The latter are connected in a circuit which includes the solenoid 168 and the main supply.

The operation of this device is as follows. In normal circumstances, i. e., with the meter in credit, the spring 181 is tensioned and the mechanism is in the position shown in Figure 11. The approaching exhaustion of credit is marked by movement of the lever 182 to depress the pin 172 to a position where it is located wholly within the stationary barrel 180. As this pin is thus freed from the slot 179 it is rotated together with the lever 173 and gear wheel 177 in an anti-clockwise direction by the spring 181 until the pin engages with the crank lever 171'. This rotary movement of the gear 177 causes rotation of the gear 184 and the cam 184a to cause intermittent opening and closing of the contacts 185 and hence intermittent energisation of the solenoid 168. The number of times the solenoid is energised may be determined by the contour of the cam 184a or by the gear ratio between the gears 177 and 184.

During the next coin-insertion operation the crank lever 171' will be rotated through one revolution in a clockwise direction and this causes similar rotation of the pin 172, lever 173 and gear 177 and the winding up of the spring 181 until the pin 172 comes into alignment with the slot 179 in the barrel 180. The spring 175 then urges the pin 172 radially outwards to lock the mechanism in the position shown in Figure 11. It will be appreciated that the lever 182 has been raised by the restoration of credit in the mechanism 21. The crank lever 171' is thus free to complete its revolution without the pin 172 and is also free to rotate idly during any subsequent coin-insertion operation while the mechanism is still in credit.

In order to permit operation of the switch contacts 185 only during the unwinding of the spring and not during reverse movement of the gear 171 upon stressing of the spring during the next coin insertion operation, a one-way drive such as a ratchet and pawl mechanism may be inserted between the cam 184a and its driving gear.

The operation of the complete mechanism is as follows: The flap 33 is lifted manually to uncover coin insertion aperture 31 and to cause movement of coin cage 25 and coin slot 29 into alignment with said aperture 31. A coin is next inserted and flap 33 released whereupon the latter is closed and the coin cage moved to the left (Figures 3, 5, and 6) by contraction of spring 36. Alignment of aperture 42 of cage 25 with coin testing chamber 44 allows the coin to fall into the latter where it is disposed between the light metal flap 50 and the metal insert 49 and rests upon the metal plate 52 on the top of the closure member 51.

The circuit thus completed if the coin is conductive sets motor 24 into operation, which operation, once started, is continued for a complete cycle of the mechanism by the shunting contacts 59. The operation of the motor causes rotation of shaft 61 whereupon the nose 122 passes into notch 121 of cam 120 to allow plunger 125 to engage thickness dimension of coin in chamber 44.

If coin is too thin or is pierceable, lower end 128 of lever 123 carrying plunger 125 engages detent device 129 so as to rock shaft 130 which in turn causes depression of bar 110 by arm 131. This lowering of bar 110 releases forked lever 54 which results in rocking of spindle 53 and consequential movement of member 51 to left (Figure 3) thereby allowing coin in chamber 44 to

fall into returned coins chute when plunger 125 is subsequently withdrawn.

If inserted coin is of suitable thickness, detent device 129 is not moved and after plunger 125 has been withdrawn the release of cam follower 82 from proud portion of snail cam 81 allows spring 104 to move slide 88 to caliper the diameter of the coin in the chamber 44. Such caliper operation causes the multi-section gear unit 89 to be set at a corresponding position along the shaft 80 so that continued rotation of latter shaft by motor 24 through gears 78, 79 brings notched disc 106 into co-operation with gauge plate 107. If the diameter of the inserted coin is not suitable, disc 106 will engage gauge plate 107 and cause rocking of bar 108 and trip lever 109 which in turn depresses bar 110 to cause release of coin into returned coins chute as already described. Movement of trip lever 109 also unlatches plate 115 from gear 79 by movement of lever 114 from pin 113 so as to allow motor 24 to complete its cycle of operation without effecting further movement of shaft 80 which is thereafter immediately returned to its initial position by pressure of cam faced lever 118 upon cam 119.

If the coin within chamber 44 is of suitable diameter then disc 106 passes through a notch in gauge plate 107 and does not rock bar 108. The consequent continued rotation of shaft 80 causes rotation of gear unit 89 and consequential movement of gear wheel 90 by an appropriate amount according to the particular section of the gear unit 89 which is effective thereon. This movement of the gear wheel 90 is transmitted to the gear 164 of the credit registering mechanism 21.

The operation of the mechanism is continued and eventually pin 143 on gear 78 engages lever 54 so as to rock it in an anti-clockwise direction (Figure 4). If the coin has already been released on account of unsuitable thickness or diameter, the fork of the lever 54 will be entered and the lever returned to its normal position and latched behind the lug 111 of the bar 110. If however the coin has proved suitable the said lever will still be latched and will be engaged by the pin 143 on the outside of the fork with the result that the said lever will be moved in an anti-clockwise direction (Figure 4) to an extent sufficient to cause rocking of the interconnected member 51 to the right (Figure 3) so as to allow the coin in the chamber 44 to fall into a coin till.

During each cycle of operation of the mechanism with either a suitable or an unsuitable coin, the gears 78, 79 and pins 144, 145 thereon are rotated one revolution. If the switch 153 controlling the current supply is already closed the pins rotate idly but if it is open the said pins engage and depress plate 146 to stress spring 151 anchored at its other end to switch rod 152 which is held latched in its upper position by lever 155. Depression of plate 146 rocks catch lever 157 which, if credit has been restored, locks up upon collar 161 and thereafter holds plate 146 in depressed position with spring 151 stressed. At a point near the end of the operative cycle of motor 24, latching lever 155 is tripped by pin 156 to allow switch rod 152 to descend rapidly under the action of spring 151 to close switch 153. The subsequent opening of the switch is effected when credit is exhausted by the removal of collar 161 from beneath end of catch lever 157 whereby tension of spring 151 is removed and the previously compressed spring 150 al-

lowed to become effective to raise the switch rod 152.

Warning of the approach of exhaustion of credit is given by the engagement of pin 164a on gear wheel 164 with lever 216 just prior to the opening of switch 153. Movement of lever 216 causes rocking of lever 182 to project pin 172 inside barrel 180. Removal of pin from slot 179 allows stressed spring 181 to rotate lever 173 and gear 177 thereby driving cam 184a to cause opening and closing of contacts 185 which in turn cause intermittent operation of solenoid 168. Energization of solenoid 168 attracts armature 170 to lift switch rod 152 to open switch 153.

The opening and closing movements of the switch rod 152 are transmitted by means of lever 191 to the gear change device 186 so that when switch rod 152 is lowered the device 186 is operated to insert the price change compound 187 between the watthour meter mechanism 12 and fixed charge collector 11 and the indicator 190 whereby the indications of the latter can be made in unused units of electricity, irrespective of the particular price per unit charge (determined by the ratio of the price change compound) whereas when switch rod 152 is raised (on account of credit exhaustion) the device 186 is operated to couple the fixed charge collector 11 and prepayment mechanism 10 directly to the pointer 190 without the price change compound so that all arrears indications are in actual cash values.

One alternative embodiment is illustrated diagrammatically in Figure 14 where a push button is employed and is first movable to a variable extent to caliper a coin. This variable movement is arranged to control a contact making operation depending upon its adjusted position when engaging the coin. As shown a push button 229 is slidably mounted in bearings, not shown, in a casing and is connected at its inner end to a plunger 221 operating into a sleeve 222 against a strong spring 223 disposed between the closed end of the sleeve and the end of the plunger. The outer face of the closed end of the sleeve 222 is used as the movable member for caliper a coin *x* against a stationary abutment 224. Any movement of the sleeve by the push button 229 is opposed by a weak spring 225 anchored at its other end to a fixed part of the device. The sleeve is connected to one end of an oscillating contact arm 226 pivoted at a point 227 such that the contact engaging end 228 executes an amplified movement to the end connected to the sleeve. This latter end sweeps over a number of contacts 229 and in dependence upon the calipered diameter of the coin *x*, rests upon one or other to set up a circuit through one of a number of electromagnets 230. These magnets actuate by ratchet and pawl mechanism a shaft 231 to varying extents according to the respective values of the coins engaged between the sleeve 222 and the abutment 224. The shaft 231 is in geared connection with the credit registering mechanism of the device. A further pair of contacts 232 are arranged in series with the switch arm 226 and contacts 229 so that after gauging the coin by the push button 229 to move the sleeve 222 against the weak spring 225 and so to choose a magnet 230 in accordance with the value of the coin, it is then necessary to press harder to overcome the pressure of the strong spring 223 and so cause closure of the contacts 232 to energize the particular magnet selected. The operation of this magnet effects the registration of credit in accordance with the value of the coin being cali-

pered. The contacts 232 may also serve to close the energizing circuit of a winding 232' for operating the switch closure device.

The above described constructional embodiment is a preferred form of the invention, but it will be understood that there are many alternative manners of carrying out the invention as defined in the attached claims.

I claim:

10. A multi-coin electricity supply meter comprising, a casing having a coin insertion aperture, a coin testing chamber receiving coins inserted in said casing through said aperture, caliper means for ascertaining the diameter of a coin in said testing chamber, credit registering means, operating means for said credit registering mechanism variably controlled by said caliper means in accordance with the diameter of the inserted coin, an electric supply switch, switch closing means for said electric supply switch, an electromagnetic device, gearing linking said electromagnetic device successively to each of said caliper, credit registering and switch closing means, and contacts for completing an energising circuit for said electromagnetic device upon insertion of a proper coin in said casing through said coin insertion aperture.
20. A prepayment electricity meter comprising, coin handling mechanism including coin receiving and coin testing means in which an inserted coin is arranged to travel step by step through the mechanism, an integrating meter for recording the consumption of energy, credit registering mechanism and means for operating the same in a credit direction in accordance with the operation of said coin handling mechanism and in a debit direction by said meter, and means controlled by said credit registering mechanism when the latter is in a position approaching zero credit for automatically and momentarily interrupting the supply circuit through said meter and for interrupting the supply when zero credit is reached until a fresh coin is inserted.
30. A prepayment electricity meter comprising, in combination, a casing having a coin insertion aperture, a coin testing chamber, caliper means operable to gauge the diameter of a coin in said testing chamber, thickness testing means arranged to gauge the thickness of a coin inserted in said coin testing chamber, an electric driving motor, means operatively connecting said caliper means and said thickness testing means with said driving motor, a shaft, credit registering mechanism, a variable ratio gear drive between said shaft and said credit registering mechanism, means for adjusting said variable ratio drive in dependence upon the operation of said caliper mechanism, a device for providing a source of power supply to said driving motor upon insertion of a coin so as to cause complete operation of said caliper and said coin testing mechanisms, and a coupling member between said motor and said shaft controlled by predetermined operation of said caliper and thickness testing devices for transmitting movement from said motor to said shaft in the event of correct coin insertion and for preventing complete movement of said shaft in the event of incorrect coin insertion whereby said registering mechanism is operated only by the insertion of a correct coin.
40. A prepayment electricity meter comprising, coin handling mechanism in which an inserted coin is arranged to travel through the mechanism, an integrating meter responsive to the energy consumption through said meter, credit reg-
45. 50. 55. 60. 65. 70. 75.

istering mechanism operable in a credit direction by said coin handling mechanism and in debit direction by said meter, a fixed charge mechanism, an indicating dial driven conjointly from said credit registering mechanism and said fixed charge mechanism, a gear change unit, and means operated by said credit registering mechanism at the point of zero credit for operatively connecting said gear change unit between said fixed charge mechanism and said indicating dial for causing the arrears to be indicated in monetary values.

5. A prepayment mechanism comprising, in combination, means for metering a commodity, means for receiving coins having different sizes each corresponding to a different value, means registering credit in accordance with the total value of the coins received and in response to the receipt of the same, means causing the commodity to be available on registration of credit by said credit registering means, fixed charge means continuously operable regardless of whether or not credit is registered and cooperating with said credit registering means to diminish the credit registered thereby, means for making said commodity available until the credit registered by said credit registering means is exhausted as a result of conjoint operation of said commodity metering means and said fixed charge means or operation of the latter alone, indicating means; means operatively connecting said commodity metering means, said credit registering means and said fixed charge means to said indicating means while credit is registered to indicate the commodity units yet available; and additional means operatively connecting said credit registering means and said fixed charge means to said indicating means after credit is exhausted to indicate the debit in coin units.

6. A prepayment mechanism comprising, in combination, means for metering a commodity, means for receiving metallic coins having differ-

ent sizes each corresponding to a different value, an electric motor, circuit means for connecting said motor to a current source including circuit connections completed on receipt of a metallic coin, means operated by said motor for testing the thickness of said coin, means controlled by said thickness testing means for rejecting a coin the thickness of which is below a predetermined value, means operated by said motor subsequent to testing the thickness of said coin for testing the diameter thereof if it has not been rejected, means operated by said motor in accordance with the diameter of said coin, and means controlled by said commodity metering means for dispensing said commodity in an amount corresponding to the diameter of said coin.

7. A prepayment mechanism comprising, in combination, means for metering a commodity, means for receiving metallic coins having different sizes each corresponding to a different value, an electric motor, circuit means for connecting said motor to a current source including circuit connections completed on receipt of each metallic coin, means operated by said motor for testing the thickness of each coin, means controlled by said thickness testing means for rejecting each coin the thickness of which is less than a predetermined value, means operated by said motor subsequent to testing the thickness of each coin for testing its diameter if it has not been rejected, credit registering means, means operatively interconnecting said credit registering means and said motor whereby the former is operated by the latter to an extent depending upon the total value of the coins received, means causing the commodity to be available on registration of credit by said credit registering means, and means cooperating with said commodity metering means for rendering said commodity available in an amount depending upon the credit registered by said credit registering means.

GEORGE EDWARD WESTON.
